UNITED STATES PATENT OFFICE

JOHN C. McCLURKIN, OF LAKIN, KANSAS

DITCHER

Application filed May 13, 1929. Serial No. 362,697.

This invention is a ditcher of the A type, and one object of the invention is to provide a novel means whereby a mold board and a land side may be swung transversely, or adjusted, about a longitudinal axis lying between the upper and lower edges of the mold board or the upper and lower edges of the land side. Another object of the invention is to provide a novel means whereby the mold board may be swung up and down, and be moved forwardly or backwardly, as occasion may require.

The invention aims to provide a ditcher of the class described which will cause the dirt to be shed off the mold board, it being possible for the operator to put the forward end of the mold board up and down into the earth to the desired depth. The invention aims to provide a ditcher which will regulate the dirt as it is pushed up the slope of a ditch by the mold board. A further object of the invention is to supply a ditcher in which the mold board may be so adjusted that the ditcher will clean all the dirt out of the bottom of the ditch.

It is within the province of the disclosure to improve generally and to enhance the utility of devices of that type to which the invention appertains.

With the foregoing and other objects in view, which will appear as the description proceeds, the invention resides in the combination and arrangement of parts and in the details of construction hereinafter described and claimed, it being understood that changes may be made in the precise embodiment of the invention, within the scope of what is claimed, without departing from the spirit of the invention.

In the accompanying drawings:—

Figures 1 shows in top plan, a device constructed in accordance with the invention;

Figure 2 is a side elevation wherein parts are broken away;

Figure 3 is a rear end elevation;

Figure 4 is a section on the line 4—4 of Figure 1.

The device forming the subject matter of this application comprises a land side and a mold board. These elements, in the draw-

ings, have been shown flat for the sake of simplicity, but it will be understood that the mold board and the land side may be concaved transversely, that being a common construction and one which the manufacturer can resort to, without specific delineation. The land side is marked by the numeral 1, and has at its lower edge, a share 2 which is removably secured in place at 3. An upper reinforcing bar, such as an angle member 4, extends lengthwise of the land side 1 on the inner surface thereof. A lower angle member 5 is secured to the inner surface of the land side 1, below the upper angle member 4 in parallel relation thereto. The members 4 and 5 are connected by a vertical inwardly extended bracket 6, shown best in Figure 3 of the drawings.

The numeral 7 designates, generally, a guide frame, the specific construction of which will be gone into hereinafter. The guide frame 7 at its forward end is pivotally connected at 8 to the forward end of the land side 1, the forward end of the guide frame being connected to the forward end of the land side by a draft hitch 9, which may be constructed as desired.

As to the specific construction of the guide frame 7, it may be said that the guide frame includes an upper bar 10 and a lower bar 11, the guide frame being disposed at an acute angle to the land side 1. The bars 10—11 of the guide frame 7 are connected at intervals by ties 12, so as to make a rigid construction. The bars 10—11 of the guide frame 7 are connected by a bracket 14, seen in Figures 4 and 1, and complementary to the bracket 6 of the land side.

Referring to Figure 3, there is shown an upper cross piece 15, an intermediate cross piece 16, and a lower cross piece 17. Above the upper cross piece 15 is located a segment 18. Pivot elements 19 connect the upper cross piece 15 and the segment 18 at their ends with the bracket 6 of the land side 1 and with the bracket 14 of the guide frame 7. Pivot elements 20 connect the intermediate cross piece 16 at its ends with the brackets 6 and 14. Pivot elements 21 connect lower cross piece 17 at its ends with the brackets 6 and 14. A

lever 22 is provided, and carries a latch mechanism 23 adapted to cooperate with the segment 18. The lever 22 is fulcrumed intermediate its ends, at 24, upon the intermediate cross piece 16. The lever 22 is pivoted at 25 to the upper cross piece 15, and the lever is pivoted at 26 to the lower cross piece 17.

A slide 27, Figure 4, is tongue-and-grooved into the bars 10 and 11 of the guide frame 7 for right line sliding movement lengthwise of the guide frame, the slide 27 being a bar of considerable length, as Figure 1 will show. On the inner edge of the slide 27 there is a rack 28.

A mold board 29 cooperates with the land side 1. A share 30 is removably secured at 31 to the lower portion of the mold board 29. Intermediate its ends, the mold board 29 is connected by a pivot element 32 with the slide 27, for vertical swinging adjustment, the pivot element 32 being located nearer to the rear end of the mold board than to the forward end, this detail being shown in Figure 2. In order to hold the forward end of the mold board 29 against swinging outwardly, transversely of the draft line, the slide 27 is provided near to its forward end with a headed stud 33 which slides in an arcuate guide 34 (Figures 1 and 4) attached to the inner surface of the mold board 29, the construction being such that the forward end of the mold board can be adjusted up and down, and, at the same time, the forward end of the mold board will be kept connected with the forward end of the slide 27.

The means for raising and lowering the forward end of the mold board 29 shows most clearly in Figure 2. It comprises a lever 37 fulcrumed intermediate its ends at 36 on a segment 35 carried by the upper bar 10 of the guide frame 7. The upper end of a link 38 is pivoted to the forward end of the lever 37 and the lower end of the link is pivoted to the forward portion of the mold board 29. The lever 37 has a latch mechanism 381 adapted to cooperate with the segment 35.

A means is provided for moving the slide 27 and the mold board 29 lengthwise, for adjustment, at the will of an operator. Having this construction in mind, a bearing 40 is secured to the guide frame 7 on the inner side thereof, as shown in Figure 1, and in this bearing a vertical shaft 41 (Figure 2) is journaled, the shaft 41 being provided at its upper end with a hand wheel 42, or something of the kind, whereby an operator can rotate the shaft at will. A pinion 43 (Figure 1) is secured to the lower end of the shaft 41 and meshes with the rack 28 on the slide 27.

The drawings show a ditcher guide, designated generally by the numeral 44. The ditcher guide will not be described in much detail, because it forms the subject matter of my co-pending application No. 304,557, filed on the 7th day of September, 1928. Let

it suffice to state that the ditcher guide 44 comprises a vertical movable axle 45 connected at 46 to one side of the ditcher, a lever 47 connected at 48 to the opposite side of the ditcher, a fulcrum connection 49 between the lever and the axle, and a ground wheel 50 journaled on the axle. The object of the ditcher guide is to enable one side of the ditcher to be adjusted vertically to control the amount of dirt that the mold board carries laterally out of the ditch, the governed supply of dirt being permitted to slip under the mold board, and the amount of dirt that the mold board scrapes out of the ditch being regulated to suit the user. With this short description, the ditcher guide, claimed in my co-pending application above referred to, may be dismissed from further consideration.

As to the operation of the device in the case at bar, first consider Figure 3: from which it is evident that the lever 22 may be swung either to the right or to the left, and be held in adjusted position by engaging the latch mechanism 23 with the segment 18. The lever 22 is pivotally connected at 25 with the upper cross piece 15, at 24 with the intermediate cross piece 16, and at 26 with the lower cross piece 17. The cross piece 15 is pivotally connected at 19 (indirectly) with the mold board 29 and with the land side 1, the intermediate cross piece 16 having a corresponding pivotal connection 20 with the mold board and the land side, and the cross piece 17 being correspondingly pivoted at 21 to the mold board and the land side. The construction is such that by shifting the lever 22, the operator can swing either the mold board 29 or the land side 1 transversely in opposite directions, as indicated by the arrows A of Figure 4, about an axis disposed intermediate the upper and lower edges of the mold board and intermediate the upper and lower edges of the land side. This construction aids in shedding the dirt off the mold board and in regulating the amount of dirt that is moved out of the ditch.

By swinging the lever 37 up and down, the forward end of the mold board 29 can be raised and lowered at the will of an operator, the lever 37 being pivotally connected by means of the link 38 with the forward end of the mold board, the mold board being pivoted at 32 to the slide 27 for vertical swinging movement. This construction enables the operator to regulate amount that the point of the mold board digs into the ground.

The operator can turn the shaft 41 by means of the hand wheel 42, and the pinion 43 on the shaft 41, cooperating with the rack 28 on the slide 27, will move the slide 27 forwardly and backwardly, the mold board 29 participating in this movement, because the mold board is connected at 32 and at 33—34 with

the slide 27. This lengthwise adjustment of the mold board 29 is useful for many purposes, not the least of which is that it will enable the operator to make a flat-bottomed ditch and also put the dirt on the top of the bank, the ordinary **A** type ditcher being inclined to keep widening the ditch at the top without getting all the dirt clean out of the bottom of the ditch.

10 I claim:—

1. A ditcher of the **A** type, comprising a land side and a mold board disposed at an angle to each other, and means for swinging the land side and the mold board transversely in opposite directions about longitudinal axes lying intermediate the upper and lower edges of the land side and intermediate the upper and lower edges of the mold board.

2. A ditcher of the **A** type comprising a land side, a guide frame pivoted at its forward end to the forward end of the land side, a slide mounted in the guide frame for right line sliding movement with respect to the line of advance of the ditcher, a mold board attached to the slide, a rack on the slide, a shaft under the control of an operator and journaled on the guide frame, and a pinion on the shaft and meshing with the rack.

3. A ditcher of the **A** type comprising a land side, a guide frame connected at its forward end to the forward end of the land side, a slide mounted in the guide frame for right line adjustment with respect to the line of advance of the ditcher, a mold board, means for pivotally connecting the mold board to the slide for vertical swinging adjustment, and means for imparting vertical swinging adjustment to the mold board.

4. A ditcher of the **A** type comprising a land side, a guide frame pivoted at its forward end to the forward end of the land side, a slide mounted in the guide frame for right line movement with respect to the line of advance of the ditcher, a mold board, means for pivotally connecting the mold board to the slide for vertical swinging adjustment, means for imparting vertical swinging adjustment to the mold board, means for imparting right line movement to the slide, and means for swinging the land side and the mold board transversely in opposite directions about longitudinal axes lying intermediate the upper and lower edges of the land side and intermediate the upper and lower edges of the mold board.

5. A ditcher of the **A**-type, comprising a land side and a mold board disposed at an angle to each other, means for swinging the land side and the mold board transversely in opposite directions about longitudinal axes lying intermediate the lower and upper edges of the land side and intermediate the upper and lower edges of the mold board, and said means comprising connections pivoted at their ends to the mold board and to the

land side, a lever pivoted to the connections, and means for holding the lever in adjusted positions.

6. A ditcher of the **A**-type comprising a land side and a mold board disposed at an angle to each other, means for swinging the land side and the mold board transversely in opposite directions about longitudinal axis lying intermediate the upper and lower edges of the land side and intermediate the upper and lower edges of the mold board and said comprising connections pivoted at their ends to the mold board and to the land side, a lever pivoted to the connections, a segment pivoted to the mold board and to the land side, and supplementing the connections as a brace between the mold board and the land side, and a latch mechanism carried by the lever and cooperating with the segment.

I testimony that I claim the foregoing as my own, I have hereto affixed my signature.

JOHN C. McCLURKIN.
